UNITED STATES PATENT OFFICE.

GEORGE TELFER, OF BELMONT, MASSACHUSETTS.

CLOTHESPIN AND ANCHOR THEREFOR.

Application filed July 24, 1922. Serial No. 576,987.

To all whom it may concern:

Be it known that I, GEORGE TELFER, a citizen of the United States of America, and a resident of Belmont, in the county of Middlesex and Commonwealth of Massachusetts, have invented certain new and useful Improvements in Clothespins and Anchors Therefor, of which the following is a specification.

10 This invention relates to a clothes pin and anchor therefor, which is especially adapted for the use of housewives in securing household articles, such as bed sheets and other linen to the ground during the drying or bleaching process.

An object of the invention is to produce a simple and inexpensive device that is effective not only to hold the article to the ground, but enables it to be held in stretched condition during the said process without injury thereto.

It is common practice among housewives to spread articles of household linen and even wearing apparel upon grass for the purpose of drying, often times leaving them out over night for the purpose of bleaching. Heretofore such articles were generally held in place by weights such as stones or small rocks, or in fact anything handy that would serve the purpose.

This was a very unsatisfactory means of securing the articles, as quite often the weights used, soiled the goods, or suitable weights could not be obtained.

35 The present invention contemplates the use of a well known clothes pin having preferably fixedly attached thereto, means to anchor said pin to the ground.

It is not known that a clothes pin has ever been used having an anchor attachment for the purpose above described and therefore it is not the intention to limit this invention to the precise construction and arrangement herein shown, as it is obvious that changes 45 might be made therein without departing from its spirit and scope.

The invention consists in certain novel features of construction which will be fully understood from a description of the drawings and the claim hereinafter given.

Referring to the drawings:

Figure 1 represents in side elevation, one

form of the improved clothes pin having an anchor attached thereto.

Figure 2 a top plan view of Figure 1.

55

Figure 3 a view looking toward the right Figure 1.

Figure 4 a view similar to Figure 1 showing another means of attaching the anchor.

Figure 5 a view looking toward the right Figure 4.

60 Like characters represent like parts throughout the several figures of the drawing.

Of the drawings:

For convenience of illustration and explanation a well known type of clothes pin is shown in the drawing herewith, having the two jaw members 10 and 11 and coiled spring 12, extensions 13 and 14 of which coacting with the notches 15, serve to retain 70 the three parts in assembled position.

Preferably the anchor member or spud 16 is loosely but permanently connected to the clothes pin in such manner that a universal relative movement between the two may be 75 obtained. It will be understood however that such movement is not necessarily essential for the successful function of the device but rather that it might be advantageous under certain conditions. Figures 1 to 3 80 inclusive show one means for attaching the said anchor 16 to the pin wherein one leg 17 of a U shaped wire is inserted into the hole 18 formed by the coiled spring 12, and headed or upset as at 19 to retain it therein, while 85 the other leg 20 is inserted between the jaws 10 and 11 to thereby prevent rotation of said wire. Previous to assembling the wire and the pin, the anchor member 16, having the eye 21, is threaded on to the wire and becomes permanently but loosely connected to 90 the pin.

Obviously this is a very simple and cheap construction and it will be observed that the anchor 16 is capable of movement relatively 95 to the pin which aids in obtaining a firm anchorage to the ground when the article is to be held in stretched condition.

The dotted lines 16^a in Figures 1 and 2 represent some of the positions the anchor 100 may assume when in use.

Figures 4 and 5 show another simple anchor member 16^x composed of a single wire, a portion of which 16^x is passed through

the hole formed by the coiled spring 12 and headed or upset at 16° to retain it in assembled relation with the pin, or if preferred it might have two anchor members as indicated by dotted lines Figure 5.

Having described the invention I claim:

In a device of the class described, a clothes pin having relatively movable jaws; a coiled spring adapted to normally retain said jaws 10 in assembled and gripping position; an

anchor retaining wire adapted to engage the coil of said spring and said jaws in such manner as to prevent its rotation; and an anchor member carried by said wire and capable of universal movement relatively 15 to said pin.

Signed by me at Boston, Mass., this 17th day of July, 1922.

GEORGE TELFER.
